DESIGN FOR A CROCHETING AND KNITTING SPINDLE

Herman E. Bishop, Bradford, Pa., assignor of one-half to Charles W. Stokes, Bradford, Pa.

Application February 19, 1941, Serial No. 99,120

Term of patent 14 years

To all whom it may concern:

Be it known that I, Herman E. Bishop, a citizen of the United States, residing at Bradford, in the county of McKean and State of Pennsylvania, have invented a new, original, and ornamental Design for a Crocheting and Knitting Spindle, of which the following is a specification, reference being had to the accompanying drawing, forming part thereof.

Figure 1 is an elevational view of a crocheting and knitting spindle, showing my new design.

Figure 2 is a top plan view thereof.

I claim:

The ornamental design for a crocheting and knitting spindle, as shown.

HERMAN E. BISHOP.
